UNITED STATES PATENT OFFICE.

IRVIN F. LEHMAN, OF PITTSBURGH, PENNSYLVANIA, ASSIGNOR TO BLAW-KNOX COMPANY, OF PITTSBURGH, PENNSYLVANIA, A CORPORATION OF NEW JERSEY.

ANNEALING BOX.

Application filed December 4, 1920. Serial No. 428,265.

To all whom it may concern:

Be it known that I, IRVIN F. LEHMAN, a citizen of the United States, residing at Pittsburgh, in the county of Allegheny and State of Pennsylvania, have invented a new and useful Improvement in Annealing Boxes, of which the following is a full, clear, and exact description, reference being had to the accompanying drawings, forming part 10 of this specification, in which—

Figure 1 is an end elevation of an annealing box embodying my invention;

Figure 2 is a top plan view of the same with a portion of the top broken away;

Figure 3 is a detail sectional view showing one of the lifting pins;

Figure 4 is a detail sectional view illustrating one step in the manufacture of the box; and

Figure 5 is a detail sectional view taken through one of the welded joints after completion.

My invention has relation to annealing boxes and more particularly to annealing boxes made up from sheet metal plates united by welding.

Heretofore, in annealing boxes of this type with which I am familiar, the welded joints are formed in such a manner as to increase the thickness of the metal at the weld, leaving on the exterior of the box more or less of a shoulder or projection. Such shoulder or projection is present not only at the vertical weld or welds but also where 30 the top or cover portion of the box is welded upon the body portion. Such projections or shoulders are extremely objectionable in use because they form surfaces which catch the impinging flames and which are attacked 35 by such flames with the result of rapid destruction of the boxes at these points.

My invention is designed to provide an annealing box formed from sheet metal in which all the welds are made in such a manner that they do not materially increase the wall thickness of the box at the welds, particularly at the outer surfaces of the box. In this manner I am able to provide a box which is of substantially uniform wall 50 thickness throughout; which is free from any shoulders or ledges of a character to form impinging points for flames; and

which, when completed, is, for all practical purposes a one-piece box.

In accordance with my invention I preferably form the body 2 of the box of a single sheet or plate of metal which is bent into generally rectangular form, with rounded corners 3, the free edges of the plate being brought together and welded. While this 60 welded joint may be made in any desired part of the box body, I prefer that it shall be at one end thereof, as indicated by the dotted line 4 in Figure 1.

5 designates the top or cover portion of the box which can be readily shaped from a single piece of metal and which is continuously welded to the upper edge of the body portion 2, as indicated by the dotted line 6.

The welds at 4 and 6 are preferably made by the water-gas hammer method. The edge portions to be welded are overlapped at a distance about equal to the thickness of the metal, as indicated in Figure 4. The overlapped portions are then brought to a welding heat by the use of a water-gas flame and the parts are then hammered until a homogeneous weld is made, the excess metal at the joint being thoroughly distributed so that in the finished article the joint is of substantially the same thickness as the balance of the box wall. The water-gas method of welding is preferably used because in such a method the metal may be brought to 80 such a temperature without danger of burning the metal.

7 designate lifting pins which are welded to opposite sides of the box in any suitable manner, such as indicated in Figure 3. In 90 this figure the lifting pins are shown as having beveled heads which are abutted against the box wall and around which metal is flowed, as indicated at 8, this metal firmly uniting the pins to the box wall.

The advantages of my invention will be apparent to those skilled in the art, since it provides a sheet metal annealing box which, for all practical purposes, may be considered as formed in one single piece of substantially uniform thickness throughout, and which is entirely free of any external shoulders or projections of a character to form attacking points for the flames.

It will, of course, be understood that the boxes may take various other specific shapes and that other changes may be made there-in within the spirit and scope of the ap-
5 pended claims.

I claim:

1. As a new article of manufacture, an annealing box comprising a sheet metal body, and a sheet metal top portion, said body and top portions being united by a continuous weld, the outer surface of which is substantially flush with the general surface of the box whereby the box is free from external shoulders at the joints, substan-
10 tially as described.
2. As a new article of manufacture, an annealing box comprising a sheet metal body, and a sheet metal top portion, said body and top portions being united by a continuous weld, the outer surface of which is substan-
15 tially flush with the general surface of the box whereby the box is free from any external shoulder at the junction of the body and top, said body being formed from a sin-
20 gle bent sheet or plate having its vertical edges brought together and united by a weld, the outer surface of which is also substan-
25 tially flush with the general surface of the box, substantially as described.

3. As a new article of manufacture, an annealing box comprising a sheet metal body and a sheet metal top portion, said body and top portions being united by a continuous welded joint, the metal at the joint being of substantially the same thickness as the other portions of the box, substantially as de-
30 scribed.

4. As a new article of manufacture, an annealing box comprising a generally rectangular body portion having rounded corners, and formed from a single sheet or plate of metal bent upon itself with its edges brought together and welded, the metal at the weld being of substantially the same thickness as the other portions of the body, and a top portion continuously welded to the upper portion of the body, the metal at this weld being of substantially the same thickness as the metal element in the body, substan-
40 tially as described.

5. As a new article of manufacture, an annealing box formed of separate sheet metal sections welded together, said box being free from external shoulders or ledges at the joints, substantially as described.

In testimony whereof, I have hereunto set my hand.

IRVIN F. LEHMAN.
